UNITED STATES PATENT OFFICE.

IVAN V. LAKICH, OF ST. LOUIS, MISSOURI.

DESIGN FOR A MEDAL.

50,023.

Specification for Design.

Patented Dec. 12, 1916.

Application filed July 10, 1916. Serial No. 108,477. Term of patent 3½ years.

To all whom it may concern:

Be it known that I, IVAN V. LAKICH, a subject of the King of Servia, residing at the city of St. Louis and State of Missouri, have invented a new, original, and ornamental Design for Medals, of which the following is a specification, reference being had to the accompanying drawing, forming a part thereof.

In the accompanying drawing in which I have illustrated my new design Figure 1 is a view showing one side of the medal; and

Copies of this patent may be obtained for five cents each, by addressing the "Commissioner of Patents Washington, D. C."

Fig. 2 is a view of the other side of the medal.

I claim:

The ornamental design for a medal, substantially as shown.

In testimony whereof, I have hereunto set my hand this 26th day of June, 1916, in the presence of two subscribing witnesses.

IVAN V. LAKICH.
